MODULATOR SYSTEM

Henry T. Winchel, Roscoe, Calif., assignor to Bendix Aviation Corporation, South Bend, Ind., a corporation of Delaware

Application February 21, 1944, Serial No. 523,303

4 Claims. (Cl. 332—38)

1

This invention relates to systems for the generation of modulated waves, and more particularly to such a system in which the percentage of modulation is maintained substantially constant despite improper loading and variation in the anode supply potential.

In a grid leak biased radio frequency class C amplifier, with constant excitation, the anode current and the alternating current anode impedance presented to the source of modulating voltage are considerably influenced by the magnitude of radio frequency load in the anode circuit of the amplifier. If, for some reason, the coupling to the load is decreased, the alternating current potential at the anode of the amplifier increases, causing an increase in the grid current thereby increasing the grid bias and plate impedance of the amplifier. As the modulating source has an appreciable impedance, this causes an increase in the magnitude of the modulating potential at the anode and/or screen of the tube bringing about deeper modulation of the radiated signal. Further, should the direct current anode supply potential decrease while the modulator output remains constant the depth of modulation will again increase. There are certain applications in which it is desirable to radiate a tone modulated signal with a substantially constant percentage of modulation, but only unskilled operators are available for handling the equipment. Under such conditions, it has been found impossible to secure satisfactory operation with the personnel available, as they frequently fail to properly adjust the anode potential and the loading reflected by the antenna circuit.

Accordingly, it is an object of this invention to provide new and novel radio transmitting apparatus in which the percentage of modulation is substantially independent of the coupling of the antenna circuit to the transmitter output circuit.

A further object of the invention is to provide new and novel radio transmitting apparatus in which the percentage of modulation is substantially independent of the anode voltage of the modulated stage.

Still another object of the invention is to provide a modulating system in which the gain of the modulating potential amplifier is controlled by variations in the load impedance in the anode circuit of the modulated stage.

Yet another object of the invention is to provide a new and novel modulating system in which the modulating potentials applied to the modulated stage are regulated in accordance with

2

variations in the load impedance in the anode circuit of said stage.

The above objects and advantages of the invention are substantially accomplished by a circuit arrangement in which the voltage drop across a resistor in the anode supply circuit of a plate and screen modulated class C final radio frequency power amplifier is employed to regulate the gain of an amplifier system supplying the modulating energy for said final amplifier.

Other objects and advantages of the invention will in part be described and in part be obvious when the following specification is read in conjunction with the drawing which is a schematic diagram of transmitting apparatus embodying the invention.

A source 10 of radio frequency energy having any desired frequency energizes the primary 11 of the driver coupling transformer 12 and is shunted by the split stator tuning capacitor 13 having a grounded rotor. The source 10 will be hereinafter referred to as the driver. The center-tapped secondary winding 14 of transformer 12 is likewise shunted by a split stator tuning capacitor 15 and the center tap of winding 14 is connected to ground through the grid leak resistor 16. In operation, the values of capacitors 13, 15 are adjusted to resonate the transformer 12 at the operating frequency of the driver 10.

The output voltage from winding 14 across capacitor 15 is balanced to ground and is applied to the control grids 17, 18 of the dual radio frequency power amplifier tube 19 having the heater 20 thermally associated with the cathodes 21, 22. Each of the sections of the tube 19 may be of the pentode type, and in the embodiment shown, the cathodes 21 and 22 are connected together within the envelope and thence to ground through the cathode resistor 23 shunted by the bypass capacitor 24. The suppressor grids 25 and 26 may also be internally connected to the cathodes of the dual sections, while the space charge grids 27 and 28 are connected together and to the positive terminal of the direct current source 29 through the dropping resistor 30 and the secondary winding 31 of the modulation transformer 32. The direct current supply circuit is completed by the connection of the negative terminal of source 29 to ground. Radio frequency potentials are eliminated from space charge grids 27, 28 by the bypass capacitor 33 connected from the grid end of resistor 30 to ground. The anodes 34 and 35 of the tube 19 are connected to either end of the center tapped primary winding 36.

of the radio frequency output transformer 37 whose center tap is also connected to the positive terminal of the source 29 through the secondary 31 of modulation transformer 32 and the parasitic suppressor including the parallel connected resistor 38 and inductor 39. Radio frequency potentials are eliminated from the winding 31 by the connection of plate bypass capacitor 40 from the tube side of winding 31 to ground.

The winding 36 is tuned to resonance with the desired frequency in the output circuit of the tube 19 by the split stator capacitor 41 connected across the end terminals thereof and the radio frequency energy appearing in this portion of the circuit is transferred to the antenna 42 through the secondary winding 43 connected across the series connected variable capacitors 44 and 45. The junction of capacitors 44 and 45 is grounded and antenna 42 is fed from the ungrounded terminal of capacitor 44. As is well known, the antenna circuit is tuned to resonance by the combined action of capacitors 44, 45 and the loading reflected into the anode circuit of tube 19 is determined by the ratio of the capacitance of 44 to the capacitance of 45 in addition to the coupling coefficient between the primary winding 36 and the secondary winding 43. Since the coupling coefficient is constant when windings 36 and 43 are fixed with respect to each other, the loading may be regarded as under the control of capacitors 44 and 45, decreasing as capacitor 44 is increased.

The system as thus far delineated operates in the conventional manner. The driving voltages on the control grids 17 and 18 cause grid current to flow, producing a voltage drop across the resistor 16 to provide a substantial portion of the operating bias for the power amplifier stage. Stray capacitances afford sufficient bypassing around resistor 16 when the apparatus operates at fairly high frequencies of the order of 10 megacycles per second. Upon tuning the anode circuit 36, 41 to resonance, the grid current and the grid bias increase, causing the anode current to decrease, with a resultant increase in the alternating current impedance presented to the secondary 31 of transformer 32. As the antenna excitation circuit including capacitors 44 and 45 is tuned to resonance, the anode current rises, the final value of the current depending upon the relative values of capacitors 44 and 45 being higher the greater the ratio of capacitance 45 to capacitance 44. These anode current changes are indicative of variations in the alternating current impedance viewed by the secondary winding 31, which variations alter the modulating voltage delivered by winding 31 and change the percentage of modulation in the output of amplifier 19. It is clearly seen, therefore, that in the conventional system thus far described the percentage of modulation is, to a material extent, affected by variations in the tuning and reflected load of the antenna circuit. This effect is eliminated by the additional apparatus now to be described.

The modulating source 46 is connected to the primary 47 of the audio coupling transformer 48 having the center tapped secondary winding 49. The center tap of winding 49 is grounded through capacitor 50 and is connected to the cathodes 21, 22 of power amplifier 19 through the series connected resistors 51 and 52 whose junction point is also grounded by capacitor 53. The end terminals of winding 49 are connected respectively to the control grids 54 and 55 of

the push-pull connected amplifiers 56 and 57 having the anodes 58 and 59 connected to the end terminals of the center tapped primary winding 60 of the audio coupling transformer 61. The electron emission necessary for the operation of the tubes 56 and 57 is provided by the emissive cathodes 62 and 63 associated respectively with the heaters 64 and 65. There is also provided a voltage divider comprising resistors 66, 67 and 68 connected in the order named between the positive terminal of source 29 and ground, the junction point of resistors 66 and 67 being grounded by bypass capacitor 69, while the junction point of resistors 67 and 68 is grounded by the bypass capacitor 70. The cathodes 62 and 63 are connected together and to the junction of resistors 67 and 68 and the center tap of winding 60 is supplied with anode excitation energy from the tap between resistors 66 and 67. The tubes 56 and 57 may be of the type having a variable pitch grid winding, commonly known as variable mu tubes, and are arranged in push-pull to minimize the production of distortion during the control actions to be later described. Resistor 68 and the bleeder current of the associated voltage divider are proportioned to maintain the cathodes 62 and 63 of amplifiers 56 and 57 somewhat positive with respect to the cathodes 21 and 22 of the radio frequency power amplifier 19.

The output energy in the anode circuits of tubes 56 and 57 appears in the center tapped secondary winding 71 of the transformer 61, whose central tap may be connected directly to ground and the end terminals of which are connected to the control grids 72 and 73 of the modulation power amplifier 74. Amplifier 74 may also be of the dual pentode type having the cathodes 75 and 76 connected together internally and to the suppressor grids 77 and 78, the combination being grounded through the bias resistor 79. The space charge grids 80 and 81 are also connected together and to the junction of the resistors 82 and 83 forming a voltage divider connected between the positive terminal of source 29 and ground. The grids 80 and 81 are maintained at ground potential for modulation frequency energy by the bypass capacitor 84 connected from these grids to ground. A heater 85 is provided for the elevation of the cathodes 75 and 76 of the modulation amplifier 74 to the required operating temperature. The anodes 85 and 86 of the power amplifier 74 are connected to the respective ends of the primary winding 87 of modulation transformer 32, said primary winding 87 being center tapped and the center tap thereof connected directly to the positive terminal of the source 29. The modulation energy appearing in the output circuit of amplifier 74 is transferred by magnetic coupling from primary 87 to secondary 31 to carry out the well known modulation process.

The operation of the complete system may now be easily understood. Amplifiers 56 and 57 are voltage amplifiers of the controllable gain type amplifying the output of modulating source 46 and supplying this amplified energy to the modulation amplifier 74, whose output in turn appears in the secondary winding 31 of transformer 32 to modulate the potentials appearing on the anodes 34, 35 and space charge grids 27, 28 of the radio frequency power amplifier 19. If for some reason the antenna system is detuned or decoupled from the anode circuit of amplifier 19, the anode current drops, decreasing the voltage across the resistor 23. This change in voltage is transmitted through the low pass filter including the resistors

51 and 52 to the control grids 54 and 55 of the amplifiers 56 and 57 causing them to become more negative with respect to the cathodes 62 and 63, thereby decreasing the gain through this stage to reduce the modulating power appearing in the secondary winding 31 and prevent an increase in the percentage of modulation of the radio frequency energy in the tank circuit including primary 36 and capacitor 41. Should the antenna load on the amplifier 19 increase, the reverse action occurs to again maintain the modulation percentage constant.

In the event that the voltage supplied by the source 29 drops, it is desirable to decrease the available modulation potential delivered from transformer 32 to prevent increase in percent of modulation or over-modulation of the radiated energy. This correction takes place in the following manner: A decrease in the anode potential applied to the amplifier 19 causes a decrease in the anode current flowing through resistor 23 with a corresponding diminution of the voltage drop thereacross. This change is again applied to the control grids 54 and 55 of the amplifiers 56 and 57 to bias them more negatively with respect to their associated cathodes and decrease the gain of the amplifier. As a result the modulating potential delivered to the power amplifier 19 is decreased in the right amount to maintain the percentage of modulation substantially constant. An increase in anode potential effects a similar correction of reversed sign.

While the heater elements of the various vacuum tubes have been shown in the drawing, the circuits for energization of same have been eliminated from the showing to simplify the presentation, it being understood that any of the many available circuits, parallel, series, etc., may be employed for the purpose.

It will be obvious that many changes and modifications may be made in the invention without departing from the spirit thereof as expressed in the foregoing description and in the appended claims.

I claim:

1. In apparatus for modulation of a carrier wave by a signal wave; a modulation amplifier tube having a cathode, a control grid and an anode; a source of carrier waves and means for applying them between said cathode and said grid; a load circuit coupled to the anode and cathode of said tube; a variable mu signal-amplifier tube having a cathode, a control grid and an anode, the amplification of which increases with increasingly positive bias on its grid; a source of signal waves and means for applying them between said grid and cathode of said signal amplifier tube; a source of unidirectional anode potential and means connecting its positive terminal to the anode of said modulation amplifier tube; means negatively biasing the grid of said modulation amplifier tube to such extent that the average cathode current increases with increasing signal output; means intercoupling

the anodes of said tubes for applying amplified signal waves from said signal amplifier tube to said anode of said modulation amplifier tube; resistance means connected between the negative terminal of said potential source and the cathode of said modulation amplifier tube for developing a potential on said cathode that is increasingly positive relative to said negative terminal with increasing cathode current; and means for applying said cathode potential to the grid of said signal amplifier tube to bias it; whereby variations in the cathode current of said modulation amplifier tube continuously produce corresponding variations in the amplitude of the signal wave.

2. Apparatus as described in claim 1 in which said means for biasing the grid of said modulation amplifier tube comprises a grid leak resistor.

3. Apparatus as described in claim 1 including means for maintaining the cathode of said signal amplifier tube at a substantially constant potential positive with respect to the negative terminal of said potential source.

4. In an anode modulated transmitter, a modulation amplifier tube having input and output circuits with means for supplying a carrier wave to the input thereof, and a signal wave source, the output of which is connected to the output of said modulation amplifier tube and to a load circuit, in combination with means for maintaining constant modulation despite variations in amplitude of the output wave of said modulation amplifier tube, said means comprising biasing means for so biasing the modulation amplifier tube that its average cathode current increases with increasing amplitude of output wave, a variable mu discharge device in said signal wave source, and means continuously responsive to variations in the unidirectional component of the cathode current of said modulation amplifier tube for varying in the same direction the amplification of said variable mu device in said signal wave source.
